[57] **CLAIM**

The ornamental design for a multi-projection multi-hole roller for massaging and chiropractic therapy, as shown and described.

DESCRIPTION

FIG. 1 is a front and left side perspective view of a multi-projection multi-hole roller for massaging and chiropractic therapy showing my new design;

FIG. 2 is a front and right side perspective view thereof; FIG. 3 is a front elevational view thereof, the top plan view and bottom plan view being the identical in appearance and the rear being a mirror image of the front shown;

FIG. 4 is a right side elevational view thereof; and FIG. 5 is a left side elevational view thereof.

FIG.1

FIG.2

FIG.3

FIG.4
